(57) **CLAIM**

The ornamental design for an ortho pliers handle, as shown and described.

DESCRIPTION

FIG. 1 is an elevated isometric view of an ortho pliers handle; FIG. 2 is a bottom side view thereof;

FIG. 3 is a right side view thereof;

FIG. 4 is a top side view thereof;

FIG. 5 is a left side view thereof;

FIG. 6 is a front side view thereof; and,

FIG. 7 is a rear side view thereof.

The broken lines shown in the figures are for illustrative purposes only and form no part of the claimed design.
